Application April 13, 1938, Serial No. 201,747

2 Claims. (Cl. 189—34)

This invention relates to improvements in building construction and more particularly to the construction of pre-fabricated sectional metal buildings, that is, buildings adapted to be erected on the desired site by the assembling of unitary sections or panels which have been previously fabricated in a factory or shop.

An object of our invention is to provide a novel form of panel unit for this type of building construction.

Another object of our invention is to provide an improved form of building construction in which panel units adapted to be connected in adjacent relation have upright channel members at their side edges disposed with the channel recesses opening outward, that is, edgewise of the panel whereby the channel members of adjacent panels cooperate in forming a hollow post.

Still another object of our invention is to provide a novel form of panel unit having connected frame members arranged to facilitate the mounting of steel sash therein.

A further object of our invention is to provide novel means for mounting vitreous enameled sheets or members on partially completed structures in which access, for connecting purposes, cannot be had to portions of the structure immediately back of such sheets or members.

Other objects and advantages of our invention will be apparent from the following description when taken in conjunction with the accompanying sheets of drawings in which

Fig. 1 is a perspective view showing building construction embodying our invention;

Fig. 2 is a perspective view showing a panel unit of the structure in detached relation and with portions thereof broken away;

Fig. 3 is a partial vertical sectional view taken through the structure of Fig. 1, as indicated by section line 3—3;

Fig. 4 is a partial vertical sectional view taken as indicated by line 4—4 of Fig. 1;

Fig. 5 is another partial vertical sectional view taken as indicated by line 5—5 of Fig. 1;

Fig. 6 is a partial transverse sectional view taken through the joint formed by adjacent panels, as indicated by line 6—6 of Fig. 1;

Fig. 7 is an elevational view, with portions broken away, illustrating one form of panel connecting means;

Fig. 8 is a detached perspective view showing the form of the transverse frame members at the ends thereof;

Fig. 9 is a perspective view showing one form

of clip for mounting vitreous enameled members on the structure;

Fig. 10 is a perspective view showing another form of clip for mounting vitreous enameled members;

Fig. 11 is a perspective view similar to Fig. 1 but showing another form of building construction embodying our invention;

Fig. 12 is a perspective view showing a panel unit of the structure of Fig. 11 in detached relation and with portions thereof broken away;

Fig. 13 is a vertical sectional view taken through one of the panels of the structure of Fig. 11 as indicated by section line 13—13;

Fig. 14 is a transverse sectional view taken through the joint between adjacent panels as indicated by line 14—14 of Fig. 11;

Fig. 15 is a perspective view showing a panel connecting clip in detached relation; and

Fig. 16 is a perspective view showing another form of clip and bolt arrangement for mounting vitreous enameled members.

More detailed references will now be made to the accompanying drawings in which we have illustrated various novel features of construction which are especially applicable to pre-fabricated sectional metal buildings. Before proceeding with the detailed description, however, we desire it to be understood that the drawings are mainly illustrative and that the invention may be embodied in various other forms of construction and type of buildings than those herein specifically described.

In Fig. 1 of the drawings we show a building having walls which have been formed by the assembling of pre-fabricated panels 21 of our novel construction on the site where the building is to be erected. The building shown in this instance is of one-story construction, such as may be desirable for automobile servicing stations or mercantile establishments, but our construction is also adaptable to other forms of buildings. The panels 21 are substantially rigid frame-like units which may be connected in edge-to-edge relation to form the walls of the building. These panels may be constructed of any size which can be conveniently handled during fabrication and erection and are preferably of a height corresponding to the height which the building is to have above the foundation.

After the panels are assembled and connected in edge-to-edge relation, the exterior of the building may be completed by mounting vitreous enameled sheets or members on the panels, and sheets of glass in the window openings provided

in the panels. The vitreous enameled members may include sheets 24 and 25 mounted on the wall in longitudinally extending series adjacent the top and bottom thereof, and horizontally extending band-like members 26 located at vertically spaced points between the sheets 24 and 25 to define the window openings in which the glass sheets 27 are mounted.

As shown in Fig. 2, the panels 21 may comprise a pair of upright frame members 30 at the side edges thereof and a plurality of vertically spaced transversely extending frame members 31 which connect the upright frame members and provide supports for the vitreous enameled members and for the glass sheets 27. The upright frame members 30 are preferably in the form of hollow channel-like members which are disposed with their channel recesses facing outward, that is, edgewise of the panel so that when the panels are disposed in adjacent relation, the channel members of such panels will cooperate to form hollow posts 32 in which ducts, pipes or wires can be housed and concealed. The upright members 30 may have any desired proportions as to their cross-sectional shape, but are preferably formed with their side flanges 33 relatively narrow so that the posts 32 will not unduly obstruct the windows 27. The flanges 33 preferably have in-turned longitudinal edge portions 34 which afford face to face contact when the panels are assembled and prevent the adjacent upright members 30 from nesting into each other.

The transversely extending frame members 31 may have their ends welded or otherwise connected to the upright members 30 to form a strong and substantially rigid frame for the panel 21. The members 31 may be hollow channel-like members which, in cross-sectional shape, have flat web or back portions 35 adapted to engage the flanges 33 of the upright members and forwardly projecting side walls 36. As shown in Fig. 3, the side walls 36 have in-turned portions 37 and also have forwardly projecting flanges 38, of narrower spacing which are connected with the in-turned portions. The forwardly projecting flanges 38 define a longitudinally extending slot-like opening 39 leading into the channel recess of this member and which opens toward the front of the panel 21. At points spaced longitudinally of the members 31 we may provide clips or sections 40, of channel-like shape or other suitable form, which are inserted between the flanges 38 and may be welded thereto. The sections 40 serve to reinforce the members 31 and also cooperate with the attaching means for the vitreous enameled members, as will be presently explained.

The transverse members 31 are spaced apart appropriate distances vertically of the panel according to the heights desired for the glass sheets and the vitreous enameled members to be mounted thereon in completing the exterior of the structure. The spacing of the members 31a and 31b, adjacent the top of the panel is appropriate for the mounting of the vitreous enameled head sheets 24 thereon. The spacing of the members 31b, 31c, 31d, 31e and 31f, is such as to provide window openings of similar height between the adjacent pairs of these members in which the glass sheets 27 may be located. The spacing of the members 31f and 31g may be appropriate for the mounting of the enameled base sheets 25 thereon.

In addition to the transverse connecting members 31, the panel 21 may have transverse metal

sheets 42 and 43 adjacent the top and bottom thereof and which have their ends connected to the flanges 33 of the upright channel members 30. The sheet 42 closes the space between the transverse members 31a and 31b and may have longitudinal flanges 44 along its top and bottom edges by which this sheet may be connected with these transverse members, as by welding. Similarly, the sheet 43 closes the space between the transverse members 31f and 31g and has longitudinal flanges 44 along its top and bottom edges which may be welded to these transverse members.

After the panels 21 have been assembled to form the walls of the building shown in Fig. 1, the roof and other parts are added to the structure until it is more or less complete and closed in with the exception of the vitreous enameled members and the glass plates 27. Since the enameled members are not applied to the structure until near the completion of the work, it will be seen that the mounting of the enameled members, and particularly the mounting of the enameled sheets 42 and 43, presents a problem because access to the panel structure immediately in back of these enameled sheets will be prevented by the metal sheets 42 and 43. However, by means of the novel connecting means which we have devised, these enameled members and sheets can be readily applied to the structure in a manner such that they will be satisfactorily held in place.

The enameled sheets 24 and 25 may be of varied construction but are preferably made with rearwardly and inwardly extending flanges 45 and 46 along their top and bottom edges. These flanges serve to strengthen the enameled sheets and to form exposed ledges on the exterior of the completed structure. In addition, these flanges cooperate with the connecting means whereby the enameled sheets are mounted on the structure. The sheets 24 and 25 may also have rearwardly and inwardly extending integral flanges 45a and 46a at their ends similar to their side flanges 45 and 46. The sheets 24 and 25 are preferably of a length substantially equal to the width of the panel 21 so that the joints between sheets correspond in location with the joints between adjacent panels.

For connecting the upper edge of the enameled sheet 24 with the top portion of the panel 21, we may provide the transverse member 31a with longitudinally spaced clips 47 which may be welded or otherwise secured to the upper flange 38 of this member. These clips are preferably spaced outwardly from the in-turned portion 37 of the member 31a so that the rearwardly and inwardly extending flanges of the upper edge of the enameled sheet 24 can be hooked over the clips and thereby mounted on the panel. Any suitable number of the clips 47 may be provided but we find that three such clips on each of the panels 21 for each of the enameled sheets 24 and 25 are sufficient. The spacing of the clips 47 outwardly from the in-turned portion 37 of the member 31a forms a longitudinally extending groove or space 49 along the top of the panel and when the enameled sheet 24 has been applied to the panel, as shown in Fig. 3, the flange portion 45 extends rearwardly over the clips and the flange portion 46 extends downwardly into the groove. After the mounting of the enameled sheet 24 on the panel has been completed as hereinafter described, a quantity of caulking material or cement 50 may be inserted into the groove 49 to fill the same.

For connecting the lower edge of the enameled sheet 24 with the transverse member 31b, we provide attaching means at longitudinally spaced points, for example three such points, 5 comprising a clip 52 and a bolt 53 extending through the clip and through the opening 54 of the section 40. The clip 52 has a plate portion 55 provided with a slot 56 and adapted to be drawn toward the member 31b and the section 10 40 thereof by means of the bolt 53. The clip also has angularly extending portions 57 and 58 which cooperate respectively with one of the flanges 38 of the member 31b and the inturned flange 46 of the enameled sheet 24.

15 The clips 52 may be connected to the sheet 24 prior to the mounting of this sheet on the panel 21, such as by welding the portion 58 of each clip to the inturned flange 46 of the enameled sheet. Prior to the application of the enameled sheet 24 to the panel, the bolts 53 are mounted in the slotted openings 56 of the clips 52 so that when the upper edge of the enameled sheet is hooked over the clips 47 and the lower end thereof is swung inwardly toward the 20 transverse frame member 31b, the bolts will extend into and through this frame member. The bolts 53 may be connected with the clips 52 as by means of nuts 60 which are screwed against opposite sides of the plate portion 55.

25 Interference between the inner nut 60 and the section 40 may be prevented by making the opening 54 of the latter large enough to freely admit this nut as shown in Fig. 3. The slot 56 of the clip 52 permits the position of the bolt 53 to be shifted on the clip so that when the enameled sheet 24 is in the desired position on the panel 21, the bolt will extend through the opening 54 of the section 40 and through an opposed opening 61 of the inner back wall or web of the 30 transverse frame member 31b. A flush type nut 62 extending into the opening 61 and having threaded connection with the bolt 53 serves as a means for tightening the bolt and thereby connecting the lower portion of the enameled sheet with the transverse frame member 31b. It will be seen that when the lower edge of the enameled sheet 24 is thus secured in place, the inturned flange portion 46 thereof extends in longitudinally spaced relation to the inturned portion 37 of the frame member 31b to form a longitudinally extending groove 63 into which the upper edge of the glass sheet 27 may extend.

35 When the enameled sheets 24 have been thus applied to the tops of the panels 21 to form a longitudinally extending row or series of such sheets, as shown in Fig. 1, the joints 64 between adjacent sheets will lie substantially opposite the joints of adjacent panels. If open cracks or spaces occur at these joints they may be filled 40 with suitable cement or caulking material.

45 The enameled sheets 25 may be mounted on the transverse members 31f and 31g at the lower ends of the panels 21 in a manner similar to that explained for the mounting of the sheets 24, but we prefer to have both the upper and lower edges of the sheets 25 connected with the transverse members 31f and 31g by means of the clips 52 and the bolts 53. In Fig. 5 we show the 50 upper edge of the enameled sheet 25 connected with the transverse frame member 31f by means of such clip and bolt and it will be understood that the lower edge of this enameled sheet may be connected with the transverse frame member 31g in a manner substantially identical with

the connection shown in Fig. 3 for the lower edge of the enameled sheet 24.

As shown in Figs. 2 and 4, the enameled members 26 are mounted on the transverse frame members 31c, 31d and 31e and cooperate with these frame members for forming longitudinal grooves 65 for the edges of the glass sheets 27. Each of the enameled members 26 may comprise an elongated channel-like strip having an outer web or face 66 and flanges 67 extending rearwardly therefrom. The flanges 67 have their rear edges 68 turned inwardly toward each other. At their ends the enameled members 26 may have rearwardly and inwardly extending integral flange portions 69 and 70, similar to the rearwardly and inwardly extending end flanges 45a and 46a of the enameled sheets 24 and 25. The enameled members 26 correspond substantially in length with the transverse width of the panel 21 so that when these strips are mounted on the 20 panels in aligned relation, as shown in Fig. 1, the joints 71 between these enameled members will lie substantially opposite the joints between adjacent panels. The cracks or spaces between the adjacent ends of the enameled members 26 may be filled by suitable cement or caulking material 72, as shown in Fig. 6. All of the transverse members 31 may have their flanges 38 cut back, as shown in Fig. 8, so as to avoid interference with the rearwardly and inwardly extending end flanges 45a and 46a of the enameled sheets 24 and 25 and with the rearwardly and inwardly extending end flanges of the enameled members 26.

In Fig. 4 we have shown, by way of example, the mounting of one of the enameled members 26 on the transverse frame member 31d. For this purpose we provide mounting means comprising a clip 74 and a bolt 75 extending through an opening of the clip and having its head 76 welded or otherwise non-rotatably connected with the clip. Any suitable number of the clips 74 may be provided for each of the enameled members 26, but we find that three such clips spaced longitudinally of this member are sufficient for each of the transverse frame members of the panel 21. The transverse frame members 31c, 31d and 31e are each provided with longitudinally spaced reinforcing sections 40 which are located thereon at the points where the clips 74 are to occur. The sections 40 may be welded to the forwardly extending flanges 38 of the transverse frame members and have a hole 78 through which the bolt 75 extends.

Each of the clips 74 may comprise a sheet metal body having forwardly projecting flanges 79 at its side edges and having ears 80 at its ends extending rearwardly in diverging relation. The width of the clip 74 is such that it can be inserted into the channel recess of the enameled member 26 and thereafter turned to a vertical position in which its rearwardly extending diverging ears 80 engage the inner faces of the inturned edges 68 of this enameled member. After the clips 74 have been inserted into the 65 enameled member 26 at the desired longitudinally spaced points and turned to their vertical position as just explained, the enameled member is applied to the transverse frame member 31d by inserting the bolts 75 through the holes of 70 the respective sections 40 and through opposed openings of the back or web 35 of this frame member. Flush type nuts 81 are then applied to the threaded inner ends of the bolts 75 and, when tightened, serve to draw the clips 74 and 75

the enameled member 26 toward the frame member 31d.

We have already stated that the panels 21, which form the wall of the structure 20, are connected in edge-to-edge relation and for this purpose any suitable form of connecting means may be employed. We have found, however, that the panels can be quickly and firmly secured together by providing cooperating connecting or locking means on the upright frame members 30 of adjacent panels. One form of such connecting means is shown in Figs. 6 and 7 and comprises a transverse bar 83 carried by one frame member and a pair of ears 84 carried by the other frame member. The bar 83 may be welded or otherwise secured to the inturned flange portions 34 of the one frame member and the ears 84 may be welded or otherwise secured to the flanges of the other frame member so as to project therefrom for engagement with said bar. The ears 84 preferably have slots 85 formed in their projecting portions and in which the bar 83 engages.

The connecting means just described may be provided at any number of vertically spaced points of the frame members of the panels 21, for example three such points, as shown in Fig. 2. When the panels are assembled the panel having the bars 83 thereon is stood in position and the panel having the ears 84 is lowered into position adjacent the first panel in such a manner that the ears hook onto the bars as the second panel assumes its proper position.

In Fig. 11 of the drawings we have shown another building structure 90 which is also formed by assembling pre-fabricated panels 91 on the building site or foundation, and thereafter completing the structure by mounting vitreous enameled sheets 92, 93 and 94 on the exterior of the panels and mounting sheets of glass 95 in the steel sash or window frames 96 which form a part of the pre-fabricated panels.

As shown in Fig. 12, each of the panels 91 may comprise a pair of laterally spaced upright channel members 98 which are disposed with their webs or backs 99 facing each other and with their channel recesses opening outward, that is, edge-wise of the panel. The frame members 98 may be similar in cross-sectional shape to the frame means 30, that is to say, they may have spaced side flanges 100 with their longitudinal edges 101 turned inwardly toward each other. These upright frame members are connected at spaced points by transverse frame members which may be of channel-like form and which have their ends welded or otherwise connected to the backs 99 of such upright members. These transverse frame members may include top and bottom members 102 and 103, and a pair of vertically spaced members 104 and 105 which cooperate with intermediate portions of the upright members to define a window opening 106 in which the steel sash 96 may be fitted and secured. Other transverse frame members may be provided at the points where they may be needed for strengthening the panel or for the mounting of the vitreous enameled sheets, such as the members 107 and 108 which are located between the transverse frame members 102 and 104.

The adjacent panels 91 may be connected in edge-to-edge relation by use of the connecting means which we have shown in Figs. 6 and 7, or if desired, another form of connecting means which we have found to be highly satisfactory may be employed. This later form of connecting means

is shown in Figs. 12, 14 and 15 and may comprise a channel shaped member or clip 110 and a bolt 111 extending through a hole 112 of the clip. The clip 110 is so formed that it will fit into the channel recess of the frame member 99 of one panel and will project therefrom into the recess of the channel member of the adjacent panel as shown in Fig. 14. In the joint formed by the use of the clip 110 and the bolt 111, the clip prevents relative transverse shifting or nesting of the adjacent channel members and the bolt prevents separation of the channel members and also serves to hold the clip in place. As shown in Fig. 12, this connecting means may be provided at vertically spaced points of the panel 91, for example, at three such spaced points.

After the panels 91 have been assembled in edge-to-edge relation, as explained above, to form the walls of the building 90 and the structure has been nearly completed by the addition of the roof and other parts, the enameled sheets 92, 93 and 94 are mounted on the exterior of the panels and the glass sheets 95 are mounted in the steel sash 96. As will be seen from Figs. 11 and 12, the enameled sheets 92, 93 and 94 correspond substantially in length with the transverse width of the panels 91 so that when these sheets are mounted on the respective panels they form longitudinally extending rows or series with the joints 113 between adjacent sheets lying substantially opposite the joints between adjacent panels. Any cracks or openings occurring at the joints 113 may be filled with suitable cement or caulking material.

As will be seen from Fig. 12 the enameled sheets 92, 93 and 94 are of pan-like form, each having rearwardly extending walls or flanges 115 at their top and bottom edges. The rear edges of these walls or flanges are deflected toward each other to form longitudinally extending inturned flanges 116. When the enameled sheets 92 and 93 are mounted on the panels by connecting means to be presently described, the walls 115 thereof form projecting ledges at the bottom and top of the window opening 106. The enameled sheet 93 may be similar to the sheet 92, but the top sheet 94 may differ from the other two in that its upper sidewall 117 may be longer or deeper so as to extend rearwardly over the top of the panel to form a coping for the wall of the building.

For mounting the enameled sheets 92, 93 and 94 on the panel 91, we provide connecting means comprising a clip 120 and a bolt 121. The clip 120 may comprise a sheet metal member having angularly disposed portions 122 and 123 which may be welded or otherwise connected to the wall and flange portions 115 and 116 of the enameled sheets. This clip may also have a plate portion 124 which is provided with a slot 125 in which the bolt 121 is mounted by a clamping of the nuts 126 against opposite faces of such plate portion. Any suitable number of clips 120 may be used on each of the enameled sheets, but we find that three such clips spaced along each of the longitudinal edges of the sheets provide a satisfactory connection. At points corresponding with the location of the clips on the enameled panels we provide the transverse frame members with holes 127 to accommodate the bolts 121. The holes in the outer flanges of the frame members, that is to say, in the flanges nearest the enameled sheets, are large enough to freely accommodate the inner nuts 126 so that the plate portion 124 of the clip 120 may engage flatly against the adjacent or outer flange of the transverse frame member.

The slot 125 of the clip 120 permits lateral adjustment for positioning of the bolt 121 with respect to the ends of the enameled sheet so that the bolts will enter the holes 127 when the sheet 5 is applied to the panel. By means of flush type nuts 128 applied to the inner ends of the bolts 121, the clips 120 may be drawn toward the transverse frame members for clamping the enameled sheets firmly in the desired position on the panel.

10 In the form of building construction shown in Figs. 11 and 12, it may be desirable to conceal the hollow posts 130 formed by the upright frame members 98 of adjacent panels and for this purpose we may mount vitreous enameled members 131 on the exterior of the building at these points. The enameled members 131 may be vertically elongated sheets of channel-like form, having rearwardly extending sidewalls or flanges 132 and inturned rear flanges 133. The enameled sheet 15 20 25 30 35 40 45

121 may be connected to the hollow post 130 by the use of the clips and bolts 135 and 136 which are substantially identical with the clips and bolts 120 and 121. The clips and bolts 135 and 136 are used in a manner similar to the clips and bolts 120 and 121, that is to say, the clips 135 are welded or otherwise connected to the sheet 131 and carry the bolts 136 so that when the sheet is applied to the hollow post, the bolts will extend through holes thereof and the sheet can be secured in place by flush type nuts 137 applied to the inner ends of the bolts. The holes 138 of the outer flanges of the frame members 98 are large enough to freely accommodate the inner nuts 139 of the bolts 136. When the enameled sheet 131 is relatively narrow, the clips 135 along opposite edges thereof are preferably arranged in offset or staggered relation so as to avoid interference with each other. After the enameled sheet 131 has been mounted on the hollow post 130 in the manner just explained, the joint between the enameled sheet and the steel sash 96 may be sealed or filled with suitable cement or caulk material 140.

From the foregoing description and accompanying drawings it will now be readily understood that we have provided improved building construction which is especially applicable to sectional metal buildings of the type formed by the

assembling of prefabricated panels or units. It will also be seen that we have provided novel connecting means for such pre-fabricated panels as well as a novel construction for the panels themselves. It will be seen furthermore that we have also provided improved connecting means for mounting vitreous enameled sheets or members on metal buildings where access to the structure immediately in back of such enameled sheets or members cannot be readily had.

While we have illustrated and described our improved building construction in a somewhat detailed manner, it should be understood, however, that we do not wish to be limited to the precise construction and arrangements of parts herein described, but regard our invention as including such changes and modifications as do not constitute a departure from the spirit of the invention and the scope of the appended claims.

Having thus described our invention, we claim:

1. In a building construction, a wall comprising unitary panels having upright channel members at their edges and disposed in abutting relation with the recesses of the adjacent channel members facing each other, a bar connected with opposite sides of one of said adjacent channel members and bridging the recess thereof, and a locking member connected with the other of said adjacent channel members to project therefrom into the recess of said one channel member and having a slot in which said bar engages.

2. In a building construction, a wall comprising unitary panels having upright channel members at their edges and disposed in abutting relation with the recesses of the adjacent channel members facing each other, one of said adjacent channel members having inturned flange portions extending toward each other, a bar extending transversely of the recess of said one channel member and connected to the backs of said inturned flange portions, and a pair of locking members connected with the other of said adjacent channel members to extend between said inturned flange portions of said one channel member and having slots in which said bar is engageable.

HARRY E. EIBER.

LAWRENCE M. DRUCKENBROD.
